EARL D. WALDRON, OF FOLSOM, CALIFORNIA, ASSIGNOR OF ONE-HALF TO EUGENE G.
PALMER, OF FOLSOM, CALIFORNIA

AUTOMATIC IGNITION-REGULATOR.

No. 924,119.

Specification of Letters Patent. Patented June 8, 1909.

Application filed November 14, 1907. Serial No. 402,119.

To all whom it may concern:

Be it known that I, EARL D. WALDRON, a citizen of the United States, residing at Folsom, in the county of Sacramento and State of California, have invented a new and useful Improvement in Automatic Ignition-Regulators, of which the following is a specification in such full and clear terms as will enable those skilled in the art to construct and use the same.

This invention relates to a governor used on gas or explosive engines for the purpose of automatically advancing and retarding the spark which explodes the gases in the cylinder of the engine.

It is a common practice to use a hand operated mechanism to advance and retard the spark in automobiles to regulate the speed of the engine, but this practice has the disadvantage that should the user of the machine fail to place the spark lever at the proper point when the engine is to be started he will be liable to be seriously injured by the engine exploding the charge of gas at the wrong time with respect to the place at which it should explode to turn the engine in the accustomed manner, the result being that the engine crank is violently thrown in the reverse direction so quickly that it will break the arm of the person trying to start the engine. This defect is sought to be avoided in this invention and at the same time means is provided to make it possible to retard or accelerate the effect of the automatic device as may be necessary.

With this invention it is impossible for the person running the automobile to leave the spark in the advanced position for the governor will at once return the spark to the "late" position when the engine has stopped, thus making it possible to start the engine at any time without danger of a premature explosion.

In the drawings in which the same numeral is applied to the same parts throughout the figures, Figure 1 is a vertical elevation of the regulator showing its mode of attachment to the cam shaft of a gas engine, Fig. 2 is a sectional view showing the inside of the circuit closer box, Fig. 3 is a sectional view showing the bearings of the circuit closer box on its shaft, and Figs. 4, 5, 6 and 7 are details of various small parts of the invention.

The regulator is applied to the engine in any position as may be convenient and is

driven from the cam shaft 1 which has a bevel gear 2 in mesh with a second bevel gear 3 carried by the governor shaft 4, said shaft 4 being journaled in boxes 5 and 6. The shaft 4 has a collar 7 which keeps the circuit closer box 8 in its proper place. Above the circuit closer box is placed the governor 9. The governor may be of any type, that shown being of the common two ball type, the clamps 10 holding it from moving at the upper end and the ring 11 moving at the lower end as the arms of the governor balls move outwardly. A ring 12 on the shaft 4 prevents the governor from rising too high, and heavy springs 13 are attached to the balls to make it certain that they will be properly retracted when the speed of the engine runs down. The ring 11 has a groove around it and a forked lever 13' takes in the groove to move the bell crank 75 about the axis 14 its other lever 15 being secured to one end of the link 16 by any suitable means, preferably by a ball and socket joint. This link 16 is connected with the circuit closer box by means of an arm 17. 80

The circuit closer is loosely hung on the governor shaft 4 ball bearings 18 being provided to make it have as little friction on the shaft as is possible. Means to lubricate the ball bearing of the circuit closer box is shown at 19. The circuit closer box is simply a ring having a hub that fits the governor shaft closely at the ball bearings and which has four holes bored through it. In each of the holes there is placed a short 90 tube 20, said tube having a collar 21 and having its outer end threaded to receive the lock nut 22. This lock nut holds the small tube 20 in place, and over the projecting end of the tube is screwed the cap 23 said cap 95 having the terminal 24. The inner end of the small tube 20 has a slot 25 cut in it to hold the small roller pin 26 in its proper position. This small roller pin 26 carries the roller 27 and it has the pin 28 projecting 100 from it at right angles with its length to make certain that the roller will at all times be held in the proper position with relation to the ring of fiber 29 so that the rollers will wear evenly and so they will not cause undue friction. The pin 26 is pressed down on the fiber roll 29 by means of a small spiral spring 31 inside the tube 20. The fiber roll has a small metal piece 30 inserted in its periphery and connected with the shaft in 105 110

order that the electrical contact may be made at the proper time.

Since it will be convenient to have the governor under manual control as well as under automatic control the rod 32 extends to such a point as may be in the reach of the person driving the machine where it is connected with the lever 33. This lever has a scale 34 under it to show the driver the position of the spark with respect to the dead center, and when it may be wished to accelerate the spark or to retard it independent of the action of the engine it may be easily done by simply pressing on the lever 33 in the desired direction, since it will then act to compress or expand the governor as the case may be. The lever 33 simply moves across the scale 34 as the governor rises or falls there being means to secure it in any fixed position.

The operation of the regulator is as follows: The machine being stopped the person who wishes to start it makes the proper engine connections and turns the crank of the engine the circuit closer box always holding the spark in the slow position at the time the engine is to be started. As the speed is increased the governor opens and the spark is advanced to such a point as may be necessary for that speed, or should the engine be stopped, or have its fuel supply

turned off the circuit closer is automatically turned back to the retarded position where there is no danger of backfiring when the engine is started.

Having thus described my invention what I claim as new and desire to secure by Letters Patent of the United States is as follows, modifications within the scope of the appended claim being expressly reserved.

In a spark timer, the combination with a driven shaft of a gas engine, a circuit closing box carried on ball bearings on said shaft, said circuit closing box having a series of plugs carrying slotted pins, rollers in the slots of said pins, a pin passing through the slotted pin and a guide for keeping the slotted pin from rotating, a governor carried by the shaft, an arm secured to the governor and to the circuit closing box and adapted to advance the spark as the speed of the engine increases, and manual means for advancing and retarding the spark at the will of the driver.

In testimony whereof I have hereunto set my hand this 2nd day of November, 1907, in the presence of the two subscribed witnesses.

EARL D. WALDRON.
